UTAH

TOWEL MACHINE

Application filed November 26, 1926, Serial No. 150,766. Renewed January 30, 1930.

This invention relates to towel machines, and particularly to what are known as machines for dispensing roller towels; and the object of the invention is to provide a machine 5 of the class specified of the simplest possible construction, and yet a machine which will be fool-proof in operation whereby the possibility of rendering the machine inoperative is practically impossible; a further object being 10 to provide a machine of the class specified, in which the towel delivery roll and the towel receiving roll are mounted to bear upon rotatable drums operatively coupled together whereby the rotation of one drum will correspondingly rotate the other, the operative connection of said drums being by a chain and sprocket construction the number of teeth on the sprockets of one drum being preferably greater than that of the other drum whereby 15 the dimensions of the extended towel loop may be maintained throughout the entire operation of the machine; a further object being to provide the front of the cabinet of the machine with two independent doors, the adjacent edges of which are spaced apart to 20 permit of the passage of toweling therebetween, one of said doors being provided with an internal catch and the other with a lock for securing said doors in closed position; a still further object being to provide an automatic stop device for stopping the rotation of the drums and the feed of toweling in each 25 revolution thereof, with means exposed through the cabinet for moving the stop into an inoperative position to permit of entire rotation of said drums and the feed of toweling, thus preventing the improper withdrawal 30 of toweling through the machine; a still further object being to provide means for preventing the withdrawal of toweling from the receiving roll; and with these and other objects in view, the invention consists in a machine of the class and for the purpose specified, which is simple in construction and operation, efficient in use, and which is constructed as hereinafter described and claimed.

The invention is fully disclosed in the following specification, of which the accompanying drawing forms a part, in which the separate parts of our improvement are desig-

nated by suitable reference characters in each of the views, and in which:

Fig. 1 is a front view of the machine, with parts of the construction broken away and in section. 55

Fig. 2 is a section on the line 2—2 of Fig. 1.

Figure 3 is a section on the line 3—3 of Fig. 1 on an enlarged scale.

Fig. 4 is a section on the line 4—4 of Fig. 3.

Fig. 5 is a side view of the framework of 60 the machine, detached from the cabinet; and,

Fig. 6 is a sectional, side view of the cabinet with the framework removed, and showing the door in a partially open position and in section. 65

In practice, we provide a cabinet comprising side walls 10 and 11, top wall 12, bottom wall 13, and a sheet metal back wall 14, the front of the cabinet being open and adapted to be closed by doors 15 and 16 which are 70 spaced apart at their adjacent edges as seen at 17 to permit the passage of toweling 18 therethrough. The lower door 16 is held in position by a catch device 19, engaging the side wall 11 of the cabinet, and the lower end of this door projects below the bottom 13 of the cabinet and is provided on its inner face with a roller 20, which extends beneath and in spaced relation to the bottom 13, and the ends of the roller are conical in form as seen at 80 21 in order to center the toweling 18 on said roller in passing into the cabinet. An ironing board 22 is secured to the inner face of the door 16 and is positioned above the bottom 13 of the cabinet and in front of the lower 85 drum 23 mounted in the cabinet, the upper drum being seen at 24. The toweling, in entering the cabinet, passes over the roller 20 through a recess 25 formed between the door 16 and the front edge of the bottom 13 of the cabinet inwardly and around the edge of the ironing board 22 and then upwardly over the drum 23, and onto the towel receiving roller 26, and this construction serves to properly straighten the toweling prior to its passage 90 onto the receiving roll.

The upper door 15 of the cabinet is held in closed position by a lock mechanism indicated at 27 in Fig. 1 of the drawing, and this door is also preferably provided with a 100

mirror 28 to add to the appearance thereof, and to render further service.

Secured to the inner face of the side walls 10 and 11 are frames 29 and 30, and each frame is provided at its upper end with L-shaped apertures 31 of the general form seen in Fig. 2 of the drawing, which open outwardly through the front edge of the separate frames to permit of the passage of the 10 towel delivery roll 32 into said apertures, and particularly the vertical portions 31^a thereof, as seen in said figure. The apertures 31 are offset as seen at 31^b to prevent the accidental displacement of the delivery roll, should the same be subjected to sudden stress, especially in pulling downwardly upon the toweling at one side thereof and with one hand, the projecting tongues 31^c operating as stops to prevent this displacement. At 15 the lower end portion of the frames 29—30 are other L-shaped apertures 33 in which the towel receiving roll 26 is mounted. These apertures are of the general construction of the apertures 31 but are not provided with 20 the projecting tongues 31^c.

The drums 23 and 24 are mounted in the frames 29 and 30 in order that said drums together with the mechanism for actuating the same may be removed from the casing as 25 a unit. Adjacent the frame 29 and outwardly thereof with reference to the wall of said frame, the drums 23 and 24 are provided with sprockets 23^a and 24^a around which a chain 34 passes. It is preferred that the sprocket 23^a be of slightly less diameter and provided 30 with one tooth less than the sprocket 24^a in order to compensate for the comparatively loose winding on the receiving roll 26 and the different nature of the fabric by being 35 subjected to moisture; the object being to maintain a towel loop 18^a of substantially the same dimensions projecting from the casing at all times, and especially preventing the 40 enlargement of such loop, which has been a difficulty in apparatus of this class. In order to aid in supporting the frames 29 and 30 in spaced relation, a coupling rod 35 is employed.

Adjacent the frame 30, the drum 24 is provided 45 with a cam or eccentric disk 36 secured to the projecting trunnion 37 of said drum, and the outer face of the cam is provided with a plurality of notches 38 in connection with which a gravity pawl 39 pivoted to the frame 30 as seen at 40, operates, to prevent 50 backward movement of said drums in the event that it be endeavored to withdraw the toweling 18 from the receiving roll 26.

The inner side face of the cam 30 is provided 55 with a projecting, arc-shaped lug 41 which is adapted to cooperate with a stop bar 42 supported in a bearing block 43 mounted in connection with the frame 30, and in 60 which the stop bar 42 is slidably mounted, 65 the bar being provided at its inner end with a

recess 44 through which the lug 41 is adapted to pass when the bar 42 is in its innermost position, which is limited by the hub portion 36^a of the cam 36. The bar 42 is provided outwardly of the recess 44 with a projecting 70 pin 45 adapted to operate in connection with the periphery of the cam 36 whereby in the rotation of said cam by the drum 24, in the direction of the arrow α , Fig. 3, the pin 45 together with the bar 42 is advanced outwardly or forwardly by said cam, this operation taking place after the lug 41 has passed through the recess 44 as seen in said figure. When the bar 42 has been advanced as above 75 stated, and on the completion of the revolution of the drum 24, the lug 41 will strike the inner end 42^a of the bar, and stop the rotation of such drum until such time as the bar 42 has been moved inwardly in the position seen in full lines in Fig. 3. This result is accomplished by a push button 46 mounted in the door 15 of the cabinet in alinement with the outer end of the bar 42, it being understood that when the bar 42 is moved outwardly, the push button 46 is correspondingly projected; and in moving the bar 42 inwardly, all that is necessary is to press the push button 46 inwardly. The inner end of the push button is provided with an enlarged head 47, which, together with the head at the outer end of the push button, prevents the displacement thereof from the door 15 when the same is swung outwardly.

In Figs. 5 and 6 of the drawing, we have shown the framework including the operative mechanisms of our improved machine, removed from the cabinet as a unit, the framework and mechanisms being shown in Fig. 5 and the cabinet with said framework removed, in Fig. 6. By virtue of this construction, the cleaning and repair of the operative mechanisms of the machine may be readily accomplished without marring or destroying the cabinet proper in any manner, and this will also facilitate the replacement of parts of the mechanism, if the same should be desired. It will also be understood that a new frame including new mechanisms may be substituted for an old one, and the old one shipped to the factory or repair shop for rebuilding or other purposes, if the same should be found to be necessary at any time.

From the foregoing, it will be apparent that after each downward pull on the toweling 18, the further withdrawal of the toweling is stopped until such time as the push button 46 is moved inwardly, thus preventing improper use of the toweling or abuse to the machine, as is a common practice in the use of the machines of the class under consideration. It will also be apparent that the application of the towel receiving and delivery rolls requires no careful threading or other manipulation, the doors 15 and 16 being swung outwardly and the rolls placed in 125 130

position, as seen in Fig. 2 of the drawing, the receiving roll 26 being first placed in position and the door 16 closed, after which the delivery roll 32 is placed in position and the door 15 closed after the required loop extension 18^a has been arranged. It will be understood that we are not necessarily limited to the specific construction and arrangement of parts herein shown and described, nor to the structural details herein set out and various changes therein and modifications thereof may be made within the scope of the appended claims, without departing from the spirit of our invention or sacrificing its advantages.

Having fully described our invention, what we claim as new and desire to secure by Letters Patent, is:—

1. In a towel machine of the class described employing drums mounted in spaced relation in the casing of the machine, said drums being coupled together whereby the rotation of one drum will rotate the other of said drums, a cam wheel mounted on the end of one of said drums, a stop bar mounted to cooperate with said cam wheel, means on said cam wheel adapted to engage said bar in one position thereof to stop further rotation of said wheel and said drums, means whereby the movement of said bar will permit of the rotation of said wheel and drums, and the periphery of said cam wheel being adapted to engage a projection on said bar to move the same into operative position in the rotation of said wheel and drums.

2. A machine of the class described comprising a casing, the front of which is open and two doors for closing said casing, a frame detachably mounted in the casing, two feed drums mounted in said frame and operably coupled together, means for supporting towel receiving and delivery rolls in said casing, one to bear upon one of said drums and the other upon the other of said drums whereby the withdrawal of toweling from the delivery roll will correspondingly wind the toweling upon the receiving roll, and the lower door of the casing extending below the bottom wall of the casing and provided on its inner face with inwardly projecting members arranged above and below the bottom wall of the casing, and projecting inwardly beyond the front edge of the bottom wall whereby the toweling passed into the casing will pass over the front edge of the bottom wall in V-fashion.

3. A machine of the class described comprising a casing, the front of which is open and two doors for closing said casing, a frame detachably mounted in the casing, two feed drums mounted in said frame and operably coupled together, means for supporting towel receiving and delivery rolls in said casing, one to bear upon one of said drums and the other upon the other of said drums whereby the withdrawal of toweling from the delivery

roll will correspondingly wind the toweling upon the receiving roll, and the lower door of the casing extending below the bottom wall of the casing and provided on its inner face with inwardly projecting members arranged above and below the bottom wall of the casing, and projecting inwardly beyond the front edge of the bottom wall whereby the toweling passed into the casing will pass over the front edge of the bottom wall in V-fashion, a lock bar slidably mounted in said frame and cooperating with one of said drums to stop the rotation thereof, and a push button mounted in one of said doors and cooperating with said lock bar to move the same into inoperative position.

4. A machine of the class described comprising a casing, the front of which is open and two doors for closing said casing, a frame detachably mounted in the casing, two feed drums mounted in said frame and operably coupled together, means for supporting towel receiving and delivery rolls in said casing, one to bear upon one of said drums and the other upon the other of said drums whereby the withdrawal of toweling from the delivery roll will correspondingly wind the toweling upon the receiving roll, and the lower door of the casing extending below the bottom wall of the casing and provided on its inner face with inwardly projecting members arranged above and below the bottom wall of the casing, and projecting inwardly beyond the front edge of the bottom wall whereby the toweling passed into the casing will pass over the front edge of the bottom wall in V-fashion, a lock bar slidably mounted in said frame and cooperating with one of said drums to stop the rotation thereof, and a push button mounted in one of said doors and cooperating with said lock bar to move the same into inoperative position, and means on said drum cooperating with said bar to move the same into operative position in the rotation of the drum.

5. A towel machine of the class described employing drums mounted in spaced relation in the casing of the machine, a slidable stop bar mounted to cooperate with one of said drums to stop the rotation thereof after each cycle of operation, means on said drum engaging said bar in one position thereof to stop the rotation of said drum, and means movable with said drum and engaging said bar to move the same into position to engage the stopping means on said drum.

6. A towel machine of the class described employing drums mounted in spaced relation in the casing of the machine, a slidable stop bar mounted to cooperate with one of said drums to stop the rotation thereof after each cycle of operation, means on said drum engaging said bar in one position thereof to stop the rotation of said drum, means movable with said drum and engaging said bar

to move the same into position to engage the stopping means on said drum, and means whereby the bar may be moved into position to permit of the rotation of said drum to start another cycle of operation.

- 5 7. In a towel machine of the class described employing drums mounted in spaced relation in the casing of the machine, said drums being coupled together whereby the 10 rotation of one drum will rotate the other of said drums, a cam wheel mounted on the end of one of said drums, a stop bar mounted to freely slide in the casing and to cooperate with said cam wheel and to be moved 15 into operative position thereby, and means on said cam wheel adapted to engage said bar when in operative position to stop further rotation of said wheel and said drums.
- 20 8. In a towel machine of the class described employing drums mounted in spaced relation in the casing of the machine, said drums being coupled together whereby the rotation of one drum will rotate the other of 25 said drums, a cam wheel mounted on the end of one of said drums, a stop bar mounted to freely slide in the casing and to cooperate with said cam wheel and to be moved into operative position thereby, means on said 30 cam wheel adapted to engage said bar when in operative position to stop further rotation of said wheel and said drums, and means whereby the movement of said bar out of operative position will permit of the rotation of said wheel and drums.

- 35 9. A towel cabinet having a towel roll and a cam element rotatable therewith and having a lug thereon, a locking bar having means thereon normally contacting said lug, said bar being longitudinally and bodily movable relatively to said lug to unlock said element, means on the bar co-operative with the cam element to restore the bar to locking position.

40 45 In testimony that we claim the foregoing as our invention we have signed our names this 22nd day of November, 1926.

EDGAR E. SHELLEY.
